UNITED STATES PATENT OFFICE.

RANDOLPH M. WARDLE, OF CARLTON, OREGON, ASSIGNOR OF ONE-HALF TO IDA LINDON, OF PORTLAND, OREGON.

IRONING BOARD.

Application filed August 15, 1927. Serial No. 213,013.

This invention is an ironing board of that general type comprising an inclined leg, a support, a platform mounted intermediate its ends on the support, one end of the platform cooperating with the adjacent end of the leg in gripping an object, and means for mounting the support for adjustment longitudinally of the leg.

The object of the present invention is to provide novel means for mounting the support for adjustment longitudinally of the leg, and so to construct the leg that the platform can be stowed away within the leg, when the platform is not in use.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:-

Figure 1 shows in side elevation, a device constructed in accordance with the invention, parts of the leg being in section;

Figure 2 is a transverse section taken through the leg;

Figure 3 is a perspective view showing one of the sleeves;

Figure 4 is a sectional view showing one of the sleeves mounted on the corresponding side member of the leg; and

Figure 5 is an elevation showing the inner side of one of the sleeves, parts being broken away.

The device forming the subject matter of this application comprises a platform P, preferably a board, an inclined leg L, a support S, and means M for mounting the support S for adjustment lengthwise of the leg L, the platform P being mounted intermediate its ends on the support S, the upper end of the leg L and the corresponding end of the platform P cooperating to grip a table T, or other object, when the lower end of the leg L rests on the floor F.

In a more detailed description, the leg L is made up of side members or bars 6 and 6^a

connected at their upper ends, and on their lower edges, by an upper cross piece 7 which engages immediately with the table T or other object, as shown in Figure 1. Near to their lower end, the side members 6 and 6^a of the leg L are connected by oppositely disposed lower cross pieces 8. It may be noted at this point that when the platform P is not in use, the platform may be mounted between the side members 6 and 6^a of the leg L, one end of the platform P being located between the lower cross pieces 8, and the other end of the platform P being disposed between the support S on the one hand, and the upper cross piece 7, on the other hand. In this way, the platform P can be stowed away in small compass, within the contour of the leg L.

The side member 6 of the leg L is provided on its upper edge with upstanding projections or pins 9. A sleeve 11, preferably made of metal, is adjustable lengthwise of the side member 6 of the leg L. The sleeve 11 is provided on its inner side with flanges 12 and 14 which extend toward each other, the inner edges of the flanges 12 and 14 being spaced apart. The flange 12 of the sleeve 11 is plain, as shown at 15 in Figure 3. In the upper wall 18 of the sleeve 11 there are holes or seats 17 adapted to receive the pins 9 on the side member 6 of the leg L. The flange 12 is somewhat shorter than the flange 14, and at the lower end of the flange 12 there is a wing 19, located in the same plane with the upper wall 18 of the sleeve 11, and at right angles to the flanges 12 and 14. The wing 19 has openings 20. The cross section of the sleeve 11 is large enough, compared with the cross section of the part 6 of the leg L, so that the sleeve 11 may be moved transversely of the part 6. In this way, the pins 9 can be disengaged from the holes 17 thereby to permit the sleeve 11 to be adjusted lengthwise of the leg L, as occasion may demand.

The side member 6^a of the leg L is provided on its inner side with projections or pins 10. The sleeve which is adjustable on the side member 6^a is shown at 11^a and its parts are designated by numerals hereinbefore used, with the suffix "a." The flange 12^a of the sleeve 11^a is provided with notches or seats 16 adapted to cooperate with the pins 10. Securing elements 21 connect the wings 19 and 19^a to the ends of the support S, the support often being in the form of a wooden bar. The securing elements 21 are located

in the openings of the wings 19 and 19^a, of which the openings 20 of the wing 19 may be regarded as typical. The sleeve 11^a can be moved like the sleeve 11, and the pins 10 can be disengaged from the notches 16. The general construction is such that the support S, along with the sleeves 11 and 11^a, may be adjusted lengthwise of the leg L as has been pointed out hereinbefore in connection with the sleeve 11.

It will be clear that the construction of the device is such that a novel means is provided whereby the support S may be adjusted lengthwise of the leg L and be held in any position to which it may have been adjusted.

What is claimed is:—

An ironing board comprising an inclined leg including spaced side members, a support, a platform mounted intermediate its ends on the support, one end of the platform cooperating with the adjacent end of the leg in gripping an object, and means for mounting the support for adjustment longitudinally of the leg; said means comprising sleeves receiv-

ing the side members of the leg and connected to the support, the upper wall of each sleeve and the corresponding side member of the leg having a releasable pin and socket connection respectively, the cross sectional area of the sleeve being large enough with relation to that of the side member of the leg so that the sleeves can be moved transversely and longitudinally of the side members, thereby to separate the pin and socket connection, and to permit the sleeves and the support to be adjusted longitudinally of the side members of the legs, one of the sleeves being provided on its side with oppositely disposed flanges, spaced apart, and a pin and socket connection between said flange and the side of the corresponding side member of the leg, the last-specified pin and socket connection being separable when the sleeve is moved transversely of the side member, as aforesaid.

In testimony that I claim the foregoing as my own, I have hereto affixed my signature.

RANDOLPH M. WARDLE.
